(57) **CLAIM**

The ornamental design for a gear cutting tool, as shown and described.

DESCRIPTION

FIG. 1 is a perspective view of a gear cutting tool.
FIG. 2 is a front elevation view thereof. A rear elevation view, a left side elevation view and a right side elevation view appear identical with the front elevation view.
FIG. 3 is a top plan view thereof.
FIG. 4 is a bottom plan view thereof.

FIG. 5 is a referential front elevation view thereof indicating an enlarged part.
FIG. 6 is a referential top plan view thereof indicating an enlarged part.

FIG. 7 is a referential bottom plan view thereof indicating an enlarged part.
FIG. 8 is an enlarged view of the portion 8 in FIG. 5.
FIG. 9 is an enlarged view of the portion 9 in FIG. 6.

FIG. 10 is an enlarged view of the portion 10 in FIG. 7; and, FIG. 11 is a referential view showing use thereof.
The broken lines shown in FIG. 11 are for the purpose of showing environmental structure only and form no part of the claimed design.

1 Claim, 11 Drawing Sheets
